UNITED STATES PATENT OFFICE.

PAUL J. SIMMEN, OF BUFFALO, NEW YORK.

AUTOMATIC RAILROAD BLOCK SYSTEM.

1,192,235.

Specification of Letters Patent. Patented July 25, 1916.

Original application filed June 3, 1907, Serial No. 377,062. Divided and this application filed October 14, 1914. Serial No. 866,639.

To all whom it may concern:

Be it known that I, PAUL J. SIMMEN, a citizen of the United States, residing at Buffalo, in the county of Erie and State of New York, have invented certain new and useful Improvements in Automatic Railroad Block Systems, of which the following is a specification.

The present invention relates to an automatic block signal system for railroads, the object of the invention being to provide a system of this character which in general will be more certain and efficient in operation than the block systems heretofore employed, and which furthermore will apprise the engine-driver or motorman whenever there is a defect in the cab circuit or in the line circuit, the present application being a division of application, Serial No. 377,062, filed June 3, 1907.

A further object of the present invention is to provide a system of this character, especially adapted for a single track railroad, in which there is a set of signals for ingoing trains and another set of signals for outgoing trains, all of which signals are normally at clear, and which are so arranged that a train passing in either direction into a part of the track between two sidings or stations will set at danger all the signals between sidings or stations for trains passing in the other direction.

In the accompanying drawings: Figure 1 is a diagrammatic view of one form of the system adapted for a double-direction single-track road. Fig. 2 is a continuation of the same and exemplifies a modification, and Fig. 3 is a diagrammatic view of the cab circuit of the two systems illustrated.

Similar reference numerals designate corresponding parts in all the figures of the drawings.

Referring to the drawings, 1 indicates a railroad track, along which is located, at spaced points, stations A, which may be in the form of sidings 79, and which divide the said track into main blocks, each of these main blocks being divided by intermediate signal stations B into sub-blocks. A series of these signal stations is located on each side of the track 1, and may be briefly described as follows, their characteristics generally corresponding to the arrangement described in the parent application, Serial No. 377,062.

Each station is provided with a group of contact rails, respectively designated 2, 3 and 4. Whenever the engine arrives at one of these contact rails, a circuit is closed in the cab, as hereinafter described. The first contact rail 2 of each group serves to notify the engine-driver to be prepared to stop before he passes the next contact rail, and, consequently the distance between these rails 2 and 3 is arranged to be the maximum distance in which any train can be stopped, as quickly as possible from its maximum speed. These rails 2 and 3 of each group are connected by a wire 6, and may therefore for electrical purposes, be considered as a continuous rail, although the signal is first given by the rail 2, and then repeated by the rail 3. These rails 2 and 3 may be made in a single continuous contact rail, but this construction is avoided on account of expense.

In the drawings, the signal devices are shown in their normal condition, and in this condition, a wire 7 leads from the rail 3 to a contact point 8, which is in contact with a contact changer 9 carried by the core 10 of the solenoids 11 and 12. Connected with said contact changer 9, is a wire 13 which leads to a wire 14, and thence to ground at 15, said ground being in this case represented by the rail of the track 1. Therefore if the contact at 8-9 is closed, the arrival of the engine both at the rail 2 and at the rail 3 closes a cab circuit, and thereby assures the engine-driver that the track ahead of him is clear. For the present, without considering other conditions that may arise, the train then proceeds until the engine arrives at the rail 4 of the same group, the effect of which is to close a circuit as follows: by a wire 17 through the front solenoid 11 of the adjacent pair of solenoids 11 and 12, then by a wire 18 leading back over the line to the rear solenoid 12 of the pair of solenoids one sub-block behind, and then by wire 14 to ground at 15. The effect of this is to energize the front solenoid 11 of the pair at the front end of the sub-block and the rear solenoid 12 at the rear end thereof, thereby attracting the core at the front end of the sub-block forward and retracting the core at the rear end of the sub-block. Since this action takes place at each sub-block or station in turn, the core at each signal station is left in its advanced position as the engine leaves said

station, and when the engine arrives at the next station in advance, said core is returned to its normal condition in which the contacts 8 and 9 are closed. Thus, as the engine passes each signal station, it separates the contacts 8 and 9 of the station immediately behind, which if closed, would actuate the clear signal in the cab, as hereinafter described, so that the succeeding train may 10 pass any station at the rear end of any sub-block, on which there is no train, but is warned against passing into a block where there is already a train. By mechanism hereinafter described, the breaking of the 15 circuit at the points 8 and 9, also actuates a danger signal in the cab of the succeeding train.

The circuit in the cab is illustrated diagrammatically in Fig. 3. Referring to said 20 figure, two shoes 21 are illustrated as carried by a hanger 22 loosely supported from the truck frame and normally depressed by springs 23 compressed between said hanger and plates 24 attached to the truck frame, 25 as shown at 25. Said contact shoes are adapted to contact successively with the contact rails 2, 3 and 4 located along the opposite sides of the track, as already explained. These rails are of the usual construction, in that they are beveled at the 30 ends, at which the shoes first make contact. From each shoe, a wire 26 leads to a switch 86 that is connected with a wire 26^a connected to a solenoid 27, then by a wire 28 to a generator 29, and from thence by wires 30 to contact points 31, which are adapted to be closed by contact arms 32 extending upward from the hanger 22. From the arms 32 lead wires 33 through a resistance 34 to 35 the contact shoes 21.

When either contact shoe 21 arrives at a contact rail, the shoe is raised and thereby breaks the circuit between the contacts 31 and 32. The breaking of this circuit, if 40 the outside circuit is not closed, deenergizes the solenoid 27, and thereby releases the core 36 thereof, which thereupon drops and strikes a bell 37, or in some other way, either directly by a danger signal, or 45 directly by the closure of a local cab alarm circuit, as is common in the art, informs the driver that the track is not clear. But if the core 10 at the signal station at which the engineer arrives has been retracted by 50 the rear solenoid 12, thereat, so that the contact is closed between the points 8 and 9 of said signal station, then the solenoid 37 is still energized, the circuit therethrough being closed as follows: from the generator 55 29 by the wire 28 through the solenoid 27, wire 26^a and one of the wires 26 to the contact shoe 21, which is in contact with one of the rails 2 or 3, by the wire 7 from said contact rail, through contacts 8 and 9, wire 13 to ground at 15, then from the ground to

the axle or other grounded portion of the engine, and by a wire 39 to the wire 30, and thence to the other pole of the generator 29. And clearly this circuit through the solenoid 27, and the ground is not closed unless 70 the contacts 8 and 9 are closed by the core 10 having been retracted by the passage of a train sufficiently far ahead.

The circuit, which is closed by the passage of the train past the contact rail 4, is 75 also closed by the cab just as it is closed by the passage over the rails 2 and 3, namely, from one of the shoes 21, wires 26 and 26^a, solenoid 27, wire 28, generator 29 and wires 30 and 39 to ground. On the outside it follows to the ground 15 at a signal station one block in the rear, and thence by the wire 14 through the rear solenoid 12 of the rear station, then returning by the line wire 18 in the manner already explained. The closing 85 of this circuit retracts the core toward the rear solenoid, and again closes the contacts 8—9, so that the clear signal may be given to succeeding trains at the rear signal station. At the same time, the passage of the 90 rail 4 gives the danger signal to the engineer, whenever for any reason the above circuit is imperfect or broken, for then no current, or an insufficient current passes through the circuit, and the core of the solenoid 27 drops, giving the danger signal.

Referring now to Fig. 3, it will be evident that either shoe 21 may be thrown into the above-described circuits on one side of the track, while the opposite shoe and the coasting signal rails and circuits can be cut out. This is accomplished by means of the switch 86, which may connect either of the wires 26 with the wire 26^a. Considering now that the said switch is positioned, as indicated in 105 Fig. 3, the shoe at the left hand side of the cab then controls the operation of the solenoid. If the switch be thrown in the other direction, then the right hand shoe controls, and the movements of the left hand shoe 110 have no effect upon the solenoid circuit.

The system disclosed in Figs. 1 and 2, as already stated, is particularly adapted to single-track railroads, in which it is desired to protect a train, not only from the approach of a train going in the same direction at the rear and at the front, but also 115 from trains going in the opposite direction.

In Figs. 1 and 2 considered as one diagram, two main blocks and three stations or sidings are illustrated, these sidings being shown at a distance from each other equal to three sub-blocks of the system. The system is intended to prevent a train moving into a block which is the part of the track 125 between two adjacent sidings, whenever any train coming in the opposite direction is between said sidings in the same block. In the case of a single track, it is desirable to have a separate series of solenoids and 130

alarm circuits for each side of the track and for trains going in opposite directions on the track, this arrangement being much simpler than one on which the solenoids on one side of the track are used for both directions, and such a system is herein illustrated.

From what has already been stated, it will be readily seen that when any ingoing train is in the position between two sidings, one or the other of the solenoids between the sidings, dependent upon the position of the train, will be set at danger. This fact is utilized in the following manner: to give the danger signal to an outgoing train to prevent it passing the first siding, and thus entering the portion of the track between the two sidings. Attached to each core of the system, is a contact plate 80. All of these contact plates are interposed in series in a wire 81 connected at one end to the ground through a contact 82 and a wire 14, the object of the latter being hereinafter explained, and connected at the other end to the contact 9 of the solenoid of the main block station at the first siding. The contacts 8 at the main block stations or sidings are connected with the ground, not directly, but through said wire 81, and it is to be noted that the wire 81 is connected with the contact 9 at the main block or siding, only on opposite sides of the track, and affects only a train going in the opposite direction, and it has no effect upon a train following in the same direction.

It might lead to inconvenient delays and stoppages if the danger signal for trains in one direction were located in the same relative position, as for trains moving in the opposite direction. For instance, if the arrangement were symmetrical for ingoing and outgoing trains, it might happen that two trains moving in opposite directions would approach two stations adjacent to sidings and give the danger signal at the same time. This obviously would stop each train, and neither could enter the track between the sidings. Each train would wait on the other, which would cause a long delay that could only be rectified by a report to headquarters. I therefore provide that the danger signal for trains in different directions is given at different relative positions. For this purpose then, for the ingoing trains, the wire 81 is extended to a contact 82 carried on the core of the next sub-block station reached by a train, before it arrives at the siding or main block station, said contact 82 carried by said core being connected to the track by the wire 14. If now, an ingoing train has passed said station, the effect will be to break said contact, and give the danger signal to an outgoing train arriving at the next siding or main block station in advance. This is effected before the

ingoing train arrives at the siding, and as soon as it passes the sub-block station next before the siding. But this is not the case with outgoing trains, as the wire 81 corresponding to the solenoids for the outgoing trains is connected only with the core of the solenoid at the siding or main block station, and the contact runs therefrom direct to the ground.

A modification is shown in Fig. 2, which is a continuation of the system from Fig. 1. Under the system as shown in Fig. 1, should the engineer disregard the danger signal and pass a siding, or main block station, when a train going in the opposite direction is between two sidings, he would get no signal from the succeeding station. In the modification shown in Fig. 2, it is provided that at each succeeding sub-block station he also gets a danger signal. It will be noted that in this disclosure, the wire 7 is connected through the pole changer 9 and wire 81 with the ground through the wire 81 on the opposite side of the track. With this embodiment it results that should the train have passed on to a track in the main block or between two sidings when a train going in the opposite direction is already in said block or between said sidings, the circuit to the ground from the wire 14 is broken and at each succeeding station the engineer would get a danger signal.

From the foregoing, it is thought that the construction, operation and many advantages of the herein described invention will be apparent to those skilled in the art, without further description, and it will be understood that various changes in the size, shape, proportion, and minor details of construction, may be resorted to without departing from the spirit or sacrificing any of the advantages of the invention.

Having thus fully described my invention, what I claim as new, and desire to secure by Letters Patent, is:—

4. In apparatus of the character described, the combination of a single track having sidings therein, a series of signal controlling devices for trains moving in one direction, a separate series for trains moving in the opposite direction, means actuated by the presence of a train successively setting at positions corresponding to danger the devices behind the train of the series corresponding to the direction in which the train is moving, and means actuated by the arrival of a train at one siding for setting at positions corresponding to danger the devices at the siding ahead, said means including a circuit on the train that is closed between the signal controlling devices, but is opened and electrically connected to said devices when the train arrives thereat.

2. An automatic railway block signal system, comprising a trackway divided into

- main blocks, each comprising sub-blocks on each side of the track, each main block and sub-block being equipped with a signal rail arranged in an indicating circuit, and a signal rail arranged in a setting circuit, in combination with a normally closed cab circuit including a source of electrical energy and an alarm element on a train, and means connecting the sub-blocks and actuated by a train for automatically setting the indicating circuits in the sub-block immediately in the rear of the train to danger and the sub-block immediately in the rear of it to safety on the same side of the track as the train and setting an indicating circuit on the opposite side of the track to danger, when such train reaches a sub-block.
3. An automatic railway block signal system, comprising a trackway divided into main blocks, each comprising sub-blocks on each side of the track, each main block and sub-block being equipped with a pair of solenoids, a circuit changer adapted to be moved thereby, a pair of indicating signal rails adapted to be in a closed circuit with a cab circuit when the circuit changer is in one position and in an open circuit when it is in another position, and a setting signal rail adapted when brought into contact with the cab circuit to energize the solenoid at a sub-station other than the one at which the signal rail is located, in combination with a source of electrical energy and an alarm element on a train, whereby as such a train reaches a sub-block its passage automatically sets the indicating circuit in the sub-block in the rear of it to safety on the same side of the track as the train and sets an indicating circuit on the opposite side of the track.
4. An automatic railway block signal system, comprising a trackway divided into main blocks, each comprising sub-blocks on each side of the track, each main block and sub-block being equipped with a signal rail arranged in an indicating circuit, and a signal rail arranged in a setting circuit, in combination with a normally closed cab circuit, including a source of electrical energy and an alarm element on a train, means on the train for automatically opening the cab circuit when a sub-block is reached, and electrical means automatically and simultaneously connected to the source of energy of the cab circuit to set the indicating circuit on the same side of the track in the first sub-block in rear of the train to danger, the second sub-block in rear of the train on the same side of the track to safety and an indicating circuit on the opposite side of the track to danger.
5. An automatic railway block signal system, comprising a trackway divided into main blocks, each comprising sub-blocks on each side of the track, each main block and sub-block being equipped with a pair of solenoids, a circuit changer adapted to be moved thereby, a pair of indicating signal rails adapted to be in a closed circuit with a cab circuit when the circuit changer is in one position and in an open circuit when it is in another position, and a setting signal rail adapted when brought into contact with the cab circuit to energize the solenoid at a sub-station other than the one at which the signal rail is located, in combination with a source of electrical energy and an alarm element on a train, and means carried by the train and electrically connected to the cab circuit for automatically opening the same when a sub-block is reached and simultaneously delivering current from said source of electrical energy through the signal rails and through certain of the solenoids to set the circuit in a sub-block in rear of the train on the same side of the track to safety conditions and set all the indicating circuits on the opposite side of the track within the main block to danger conditions.
6. An automatic railway block signal system, comprising a single trackway divided into main blocks, each comprising two sets of sub-blocks respectively for oppositely moving trains, a normally closed cab circuit, means for opening the cab circuit at each sub-block station and block station and completing it through mechanism in said block station outside the cab, and means operated by mechanism in said completed circuit at said block station for establishing a danger signal in the cab of a train moving in the same direction in rear of the said first-mentioned cab, and in the cab of a train moving in the opposite direction in advance of the first-mentioned cab.
7. An automatic railway block signal system, comprising a single trackway divided into main blocks, each comprising two sets of sub-blocks, respectively, for oppositely moving trains, a normally closed cab circuit, means for opening the cab circuit at each sub-block station and block station and completing it through mechanism in said block station outside the cab, means operated by mechanism in said completed circuit at such block station for establishing a danger signal in the cab of a train moving in the same direction in rear of the said first-mentioned cab and in the cab of a train moving in the opposite direction in advance of the first-mentioned cab, and means for repeating the danger signal in the advance cab at each sub-block station passed thereby.
8. An automatic railway block signal system, comprising a single trackway divided into main blocks, each comprising two sets of sub-blocks, respectively, for oppositely moving trains, a normally closed cab circuit, means for opening the cab circuit at each

- sub-block station and block station and completing it through mechanism in said block station outside the cab, a solenoid in said completed circuit outside the cab, and means 5 operated by the said solenoid when energized by said circuit for preventing the closing of a similar cab circuit at a sub-block station in rear and for permitting the closing of a circuit in the second sub-block station in rear, 10 and for preventing the closing of a circuit at a sub-block station in advance.
9. An automatic railway block signal system, comprising a single trackway divided into main blocks, each comprising two sets 15 of sub-blocks, respectively, for oppositely moving trains, a normally closed cab circuit, means for opening the cab circuit at each sub-block station and block station and completing it through mechanism in said block 20 station outside the cab, a solenoid in said completed circuit outside the cab, and means operated by the said solenoid when energized by said circuit for preventing the closing of a similar circuit at the first main block station in rear, at a main block station in advance, and at each sub-block station between the said main block station in advance and the cab at which the said circuit is closed.
10. An automatic railway block signal 25 system, comprising a single trackway divided into main blocks, each of said main blocks being divided into two sets of sub-blocks, one set for trains moving in one direction, the other set for trains moving in 30 the opposite direction, a set of signal controllers for one set of sub-blocks, a set of
- signal controllers for the opposite set of sub-blocks, and means controlled by a train entering a main block in one direction for setting at danger the opposite signal controller 40 at the other end of the main block and the signal controller of each opposite sub-block in said main block, said means including devices on the train for indicating clear and danger conditions of said system. 45
11. An automatic railway block signal system, comprising a single trackway divided into main blocks, each of said main blocks being divided into two sets of sub-blocks, one set for trains moving in one direction, the other set for trains moving in 50 the opposite direction, a set of signal controllers for one set of sub-blocks, a set of signal controllers for the opposite set of sub-blocks, and means controlled by a train entering a main block in one direction for setting at danger the opposite signal controller at the other end of the main block, the signal controller of each opposite sub-block in said main block, and the signal controller for trains operating in the same direction as and located in rear of said train, said means including devices on the train for indicating clear and danger conditions of 55 said system. 60

In testimony whereof I affix my signature in presence of two witnesses.
